(57) CLAIM

The ornamental design for a fuse block with removable clear plastic cover, as shown and described.

DESCRIPTION

FIG. 1 is a perspective view of a fuse block with removable clear plastic cover showing my new design.

FIG. 2 is a front view of the fuse block with removable clear plastic cover shown in FIG. 1.

FIG. 3 is a right end view of the fuse block with removable clear plastic cover shown in FIG. 1.

FIG. 4 is a top view of the fuse block with removable clear plastic cover shown in FIG. 1; and,

FIG. 5 is a bottom view of the fuse block with removable clear plastic cover shown in FIG. 1.

The fuse block with removable clear plastic cover illustrated in the drawings is symmetric, wherein a rear view is the same as the front view shown in FIG. 2, and a left end view is the same as the right end view shown in FIG. 3. Also, a curved, clear plastic cover covers the fuse area.
